UNITED STATES PATENT OFFICE.

JOHN FOXALL, OF NEWPORT, COUNTY OF MONMOUTH, ENGLAND, ASSIGNOR
TO THOMAS WALTERS, OF SAME PLACE.

DRY GAS-METER.

SPECIFICATION forming part of Letters Patent No. 247,733, dated September 27, 1881.

Application filed June 29, 1881. (Model.) Patented in England July 23, 1880.

To all whom it may concern:

Be it known that I, JOHN FOXALL, a citizen of the Kingdom of Great Britain, residing at Newport, in the county of Monmouth, England, have invented certain new and useful Improvements in Gas-Meters; and I do hereby declare the following to be a full, clear, and exact description of the invention, such as will enable others skilled in the art to which it appertains to make and use the same, reference being had to the accompanying drawings, and to the letters or figures of reference marked thereon, which form a part of this specification.

This invention relates to certain improvements in dry gas-meters; and it has for its object to provide a meter which will register more accurately and give a more steady and uniform light than heretofore. These objects I attain by the apparatus illustrated in the accompanying drawings, in which—

Figure 1 represents a transverse vertical section of my improved meter. Fig. 2 represents a top view with portions broken away, showing the interior mechanism. Fig. 3 represents a detached view, showing the valve-ports for the induction and eduction of the gas; Fig. 4, a detached view, showing the passages leading from the bellows at each side of the diaphragm to the eduction-tube of the meter. Fig. 5 is a reverse view of the valve; and Fig. 6 is a side elevation, partly in section.

The letter A indicates a casing of sheet metal, which is preferably rectangular, but which may be made in any other desired shape. The said casing is divided into three compartments, B, C, and D, by means of the vertical diaphragm E and the horizontal partition F. In the compartment D is located a chamber, G, into which extends and with which communicates the gas-induction pipe H. The said chamber is provided with the ports I, K, L, M, and P, as clearly shown in Fig. 3 of the drawings, the ports I and K leading directly into the compartments B and C at each side of the vertical diaphragm. The ports L and M connect, by means of passages R and S and apertures T and U, with the interior of the bellows or flexible chambers V' and V, located, respectively, in the compartments B and C. The central port, P, leads to a pipe, W, connecting with the eduction or service-pipe Y of the apparatus. The gas comes

in the induction-pipe H and fills the chamber G. When the open part C' of the valve A' is over the port L the gas passes through it into the passage S and opening U into the bellows V', causing it to expand. This motion is communicated to the valve A', causing it to rotate and place the open part C' over M. Then the gas is cut off in its passage into V', and passes through port M, passage R, and opening T into bellows V, causing it to expand. Thus the alternate motion is kept up. When the open part C' of the valve A' is over L the exhaust-recess D' is over K, which is open to compartment B, and the gas contained in it flows into the central port, P, and thence out through W to the exit-pipe Y; and when the part C' is over M the exhaust-recess D' is over I, which communicates with compartment A, and the gas contained therein escapes into the central port, P, and thence outward, through W, into the exit-pipe Y.

The letter A' indicates a rotary valve, which is located and adapted to move upon a seat, B', formed around the ports I, K, L, M, and P. The said valve is in the form of a disk, cut away at the edge to the extent of one of the ports above mentioned, as indicated by the letter C', and having a recess, D', on its under side. The valve on said under surface is provided with a packing of leather or other equivalent material, as indicated by the letter F'.

The letter G' indicates a valve-stem secured to the rotary valve and passing upward through a stuffing-box, H', the outer extremity being provided with a worm-screw, I', which intermeshes with suitable gearing connected with an index or pointer, to indicate, in connection with a suitable dial, the quantity of gas passed through the apparatus. The said valve-stem, at its outer or upper end, is provided with a horizontal crank, K', to which are pivoted the connecting-rods L', which are in turn pivoted to the arms M', secured to the vertical rods N', passing through stuffing-boxes O', the lower ends of said rods connecting with the respective bellows or flexible chambers by means of the arms N'. It will thus be seen that, as the bellows are alternately expanded and contracted, they communicate motion to the vertical rods N' through the arms N', and the rods N' in turn operate the arms M'. Up to this

point the motion communicated by the bellows is a reciprocating one; but the connecting-rods L', connecting the arms M' with the crank K', convert it into a rotary motion, and, as the crank K' is secured to the stem of the valve A', it has a standard rotary motion with reference to the bellows.

Having thus described my invention, what I claim, and desire to secure by Letters Patent, is—

1. In combination with the casing, the vertical diaphragm, and horizontal partition, the eduction-passages leading from the bellows or flexible chambers to the central port of the valve connecting with the eduction-port of the meter, substantially as and for the purposes specified.

2. The combination, in a gas-meter divided into three compartments, of the bellows, the induction-chamber and its ports, the rotary valve and its valve-stem, and mechanism for operating a register, and the eduction-pipe connecting the central port of the valve with the exit-pipe, substantially as and for the purposes specified.

In testimony whereof I affix my signature in presence of two witnesses.

JOHN FOXALL.
